CLAIM

The ornamental design for a plastic wrap dispenser, as shown and described.

DESCRIPTION

FIG. 1 is a front perspective view of a plastic wrap dispenser of the present invention.

FIG. 2 is a back perspective view of FIG. 1.

FIG. 3 is a front view of FIG. 1.

FIG. 4 is a back view of FIG. 1.

FIG. 5 is a left view of FIG. 1.

FIG. 6 is a right view of FIG. 1.

FIG. 7 is a top view of FIG. 1; and,

FIG. 8 is a bottom view of FIG. 1.

The broken lines in the figures illustrate portions of the plastic wrap dispenser and form no part of the claimed design.

1 Claim, 8 Drawing Sheets
